UNITED STATES PATENT OFFICE.

PETER P. COOPER, OF PHILADELPHIA, PENNSYLVANIA, ASSIGNOR TO WESTINGHOUSE ELECTRIC AND MANUFACTURING COMPANY, A CORPORATION OF PENNSYLVANIA.

ELECTRIC LOCOMOTIVE.

1,308,044.

Specification of Letters Patent. Patented July 1, 1919.

Application filed January 14, 1918. Serial No. 211,776.

To all whom it may concern:

Be it known that I, PETER P. COOPER, a citizen of the United States, and a resident of Philadelphia, in the county of Philadelphia and State of Pennsylvania, have invented a new and useful Improvement in Electric Locomotives, of which the following is a specification.

This invention relates to electric locomotives and particularly to locomotives of jointed six-wheel or eight-wheel mine and industrial types.

The principal object of the invention is to form a jointed locomotive having six or more wheels, by combining one or more inexpensive auxiliary motor sections with the usual four-wheel type of mine and industrial locomotive. When a four-wheel locomotive becomes inadequate to meet the increased demands in the work for which it is employed, in order to obtain a more powerful locomotive, it has heretofore been necessary to use a standard six-wheel rigid-frame locomotive. However, by means of my invention, it becomes possible to readily convert the four-wheel locomotive in use into a jointed six-wheel or eight-wheel locomotive of greater capacity at a small expense by combining therewith one or more auxiliary motor sections.

A further object of my invention is to provide a jointed locomotive consisting of two or more unitary motor sections flexibly connected together by coupling members that will maintain the ends of the two body parts of the locomotive in abutting relation but will permit these parts to move laterally with relation to each other.

The above and other objects and the novel features of the invention will be apparent from the following description, taken in connection with the drawings which constitute a part of this application and in which Figure 1 is a plan view of a jointed six-wheel locomotive embodying my invention, parts thereof being broken out to show the construction of the flexible coupling. Fig. 2 is a side elevation of the locomotive shown in Fig. 1, with parts broken out to disclose the construction of the coupling member. Figs. 3 and 4 are, respectively, a plan view and a central sectional view of a portion of a locomotive similar to the one illustrated in Figs. 1 and 2 but disclosing a different form of flexible coupling. Figs. 5 and 6 are,

respectively, a plan view and a central sectional view of flexible coupling means embodying my invention. Figs. 7 and 8, respectively, are a plan view and a side elevation illustrating another form of flexible coupling embodying my invention; and Figs. 9 and 10 are, respectively, a plan view and a side elevation illustrating another form of flexible coupling embodying my invention.

Referring to Figs. 1 and 2, 10 represents a body of the usual four-wheel mine and industrial type of electric locomotive. The body is low and supported, by springs 11 and 12, on the axles 13 and 14, respectively. The axle 13 has a pair of drive wheels 15 fixed thereon, and the axle 14 has a pair of trailer wheels 16 fixed thereon. The propelling means of the four-wheel section consists of an electric motor 17 which is geared to the drive wheels 15 and is controlled by a suitable controller 18 mounted on the front end of the body 10 in the usual manner.

The two-wheel auxiliary motor section consists of a body part 19 which is supported by springs 20 on a single axle 21 that has wheels 22 fixed thereon. The auxiliary body section 19 is substantially the same size in transverse section as the main body part but is considerably shorter than the latter. An electric motor 23 is mounted on the auxiliary body part 19 and is geared to the wheels 22 to drive the same. The motor 23 may also be controlled from the controller 18 by a suitable connection.

The main and auxiliary body parts of the locomotive are connected together by a suitable flexible coupling device that will maintain the two body parts in abutting relation but which will permit these parts to move laterally and vertically with relation to each other. In the form of coupling device employed in the locomotive shown in Figs. 1 and 2, the opposed ends of the body sections 10 and 19 are provided with sockets 24 and 25 to receive the ends of the coupling device 26. The end of the coupling device which fits in the socket 24 has a horizontal hole therethrough to receive a coupling member 27 that connects the propelling member to the body section 10, and the end of the coupling member which is disposed in the socket 25 has a hole extending vertically therethrough to receive the coupling pin 28 that pivotally connects the coupling

to the auxiliary body part 19. The opposed end faces of the body parts 10 and 19 are curved or so shaped that there will be a clearance between them at all points around the peripheries of the body parts, the clearance diminishing toward the center of the ends where they are in abutting relation. The socket 24 is also of sufficient size to permit the bodies 10 and 19 to move freely in a vertical direction with relation to each other, and the socket 25 is also of such size that the bodies 10 and 19 may move laterally with relation to each other.

From the foregoing description, it will be seen that I have provided a jointed six-wheel locomotive by flexibly connecting an inexpensive auxiliary motor section to the usual four-wheel type of locomotive. The construction thus formed is superior to the ordinary six-wheel rigid-frame locomotive because the jointed type is adapted to round curves of shorter radius. Another advantage of this construction is that the owner of a four-wheel locomotive may convert the same into a six-wheel locomotive of greater capacity by combining the auxiliary motor section therewith, or he may disconnect the auxiliary motor section from the four-wheel section where the work does not require the use of the six-wheel locomotive.

Where the work demands a locomotive of greater capacity than that afforded by a jointed or rigid six-wheel locomotive, it will be obvious that a two-wheel auxiliary motor section, such as I have disclosed, may be employed to form an eight-wheel jointed locomotive. This may be accomplished by coupling a two-wheel motor section to each end of the usual four-wheel locomotive or by coupling a single two-wheel motor section to one end of a six-wheel rigid frame locomotive. The parts of the locomotive are, of course, articulated together in the same manner as in the six-wheel locomotive illustrated in the drawing. The main and auxiliary motor sections may be controlled from a single controller mounted at any desirable place, but, for the sake of clearness, the electrical connections are omitted.

In Figs. 3 and 4, I have illustrated another form of flexible coupling in which the coupling member 29 has two draft arms 30, the ends of which are secured to the sides of the auxiliary motor section. The front end of the coupler 29 is adapted to fit into a socket 31 in the main body section 10 and is held in position by a coupling pin 32. The abutting faces of the bodies are provided with a tongue 33 and a groove 34, respectively, to form a sliding connection between bodies 10 and 19, the groove 34 being of sufficient length to permit lateral movement of the bodies with relation to each other.

In Figs. 5 and 6, is illustrated another form of coupling which is, in most respects,

similar to that shown in Figs. 3 and 4 except that a supporting plate 35 is provided on the main body section 10 to support the coupling member 29.

In Figs. 7 and 8, a flexible coupling connection is provided between the side frame parts of the two bodies. Each side frame member of the body 10 has a groove 36 therein to receive the tongue 37 on the side frame of the auxiliary body 19. A pin 38 passes through an opening in the side frame of the body 10 and through the tongue 37 to flexibly connect the bodies together.

In Figs. 9 and 10, I have illustrated a form of flexible coupling which differs slightly from that shown in Figs. 7 and 8, in that plates 39 are riveted to opposite sides of the side-frame members on the auxiliary body 19 to form a groove or socket to receive the end of the side-frame members of the body 10. A pin 40 which passes through the plates 39 and the side-frame member of the body 10 flexibly connects the frames together at each side of the locomotive.

While I have shown and described the preferred form of my invention, and several modifications thereof, I do not wish to be limited to the exact constructions illustrated, as it is obvious that numerous changes may be made therein without departing from the spirit of the invention.

I claim as my invention:

1. In an electric locomotive, the combination with a main section having a plurality of axles and wheels thereon and equipped with electric motive means, of a two-wheel auxiliary section equipped with motive means, and coupling means for flexibly connecting said sections.

2. In a mine or industrial type locomotive, the combination with a comparatively low four-wheel main body section, of a comparatively low two-wheel auxiliary body section, a propelling motor mounted on each section, and a coupling device for flexibly connecting said sections.

3. In a mine or industrial-type electric locomotive, the combination with a main body section equipped with a plurality of axles, wheels on said axles, and electromotive means for driving the wheels on one of said axles, of an auxiliary body section equipped with a single axle, wheels on said axle, electromotive means on said auxiliary body section for driving the wheels on said single axle, and coupling means for flexibly connecting said sections.

4. A jointed mine and industrial-type electric locomotive comprising a main low body part equipped with a plurality of axles, wheels on said axles, electromotive means on said main body part for propelling the same, an auxiliary body part of substantially the same size in transverse section as the main body part but shorter than the

latter, a single axle on said auxiliary part, wheels on said axle, electromotive means on said auxiliary part for propelling the same, and flexible coupling means for connecting 5 said body parts together.

5. In an electric locomotive, the combination with a four-wheel main body part equipped with electromotive means, of a two-wheel auxiliary body part equipped

10 with electromotive means, the adjoining ends of said body parts being in abutting relation and so shaped as to permit free lateral motion of one body part with relation to the other while maintaining the abutting relation, and flexible coupling means for connecting 15 said body parts together.

6. In an electric locomotive, the combination with a four-wheel main body part equipped with electromotive means, of a

20 two-wheel auxiliary body part equipped with electromotive means, and means for connecting said body parts together comprising a coupling member secured to one of the body parts and a pin flexibly connecting 25 said member to the other body part.

7. In an electric locomotive, the combination with a main body part equipped with a plurality of axles, wheels thereon, and electromotive means, of a two-wheel auxiliary body part equipped with electromotive means, and means for connecting said body parts together comprising a coupling member secured to the auxiliary body part and a pin in the longitudinal center-line of the 30 main body part flexibly connecting said member to the main body part.

8. In an electric locomotive, the combination with a main body part equipped with a four-wheel running gear and electromotive 40 means for propelling the same, of an auxiliary body part equipped with a two-wheel running gear and electromotive means for propelling the same, the adjoining ends of said body parts being in abutting relation 45 and so shaped as to permit free lateral and vertical movement of said body parts relatively to each other while maintaining the abutting relation, and means for connecting said body parts together comprising sockets 50 in the abutting ends of said members and a coupling member having portions disposed in said sockets and connected to one of said body parts by a vertical pin and to the other body part by a horizontal pin.

55 9. In a jointed mine and industrial type electric locomotive, in combination, a main low body part, running gear therefor in-

cluding a plurality of axles and wheels thereon, springs supporting said body part on its running gear, electromotive means 60 mounted on said running gear for propelling the main body, an auxiliary body part of substantially the same size in transverse section as the main body part but shorter than the latter, a single axle on said 65 auxiliary part, wheels on said axle, electromotive means on said auxiliary part for propelling the same, the adjoining ends of said body part being in abutting relation and so shaped as to permit free motion of 70 said body parts relatively to each other while maintaining their abutting relation, and means for connecting said body parts together comprising a coupling member secured to one of the body parts and a pin 75 flexibly connecting said coupling member to the other body part.

10. The combination with an electric locomotive, of an auxiliary motor section comprising a body portion, a pair of wheels for supporting said body portion, propelling means mounted on said body portion, and means for coupling said body portion to the electric locomotive.

11. In an auxiliary motor section adapted 85 to be coupled to a locomotive, the combination with a body, of a single axle and pair of driver wheels for supporting the same, an electric driving motor mounted on the body rearwardly of the axle and connected 90 to said driver wheels, and means at the front end of the body for flexibly coupling it to a locomotive, the front end of the body being shaped to adapt it to move angularly with respect to the locomotive to which it is 95 coupled while maintaining abutting relation therewith.

12. In an auxiliary motor section adapted to be coupled to a locomotive, the combination with a body having one end thereof 100 equipped with coupling means and shaped to adapt it to maintain abutting relation with a similarly shaped main motor section to which it may be coupled, of a single axle and a pair of driver wheels for supporting the said body, and an electric driving motor connected to said driving wheels and disposed on the side of said axle away from 105 said coupling end.

In testimony whereof, I have hereunto 110 subscribed my name this 27th day of December 1917.

PETER P. COOPER.
